UNITED STATES PATENT OFFICE.

GEORGE A. BISHTON, OF CEDAR RAPIDS, IOWA.

GROUNDING DEVICE.

1,092,009.

Specification of Letters Patent. Patented Mar. 31, 1914.

Application filed February 10, 1912. Serial No. 676,772.

To all whom it may concern:

Be it known that I, GEORGE A. BISHTON, a citizen of the United States, residing at Cedar Rapids, in the county of Linn and 5 State of Iowa, have invented new and useful Improvements in Grounding Devices, of which the following is a specification.

This invention relates to grounding devices and has special reference to the means 0 for planting or driving the grounding device into the earth so as to insure perfect electrical contact with the ground for any of the usual purposes.

By means of this invention, a thin flexible 5 conducting strip may be driven into the ground without danger of injury to the same during the driving operation or during the removal of the driving element. The use of a thin grounding element insures perfect 0 electrical contact at all times and also economizes in the manufacture of devices of this nature. The grounding strip herein-after described may, by means of the driving device, be planted at any desired distance 5 below the surface of the ground to avoid the deleterious effects of freezing and dryness of the earth near the surface, both of which conditions would greatly impair the efficiency of the grounding device.

With the above and other objects in view, 0 the invention consists in the construction, combination and arrangement of parts, set forth in and falling within the scope of the appended claim.

In the accompanying drawing:—Figure 1 is a sectional view, showing the grounding device in its entirety, including the driving element and the point. Fig. 2 is a side elevation of the driving point. Fig. 3 is a similar 5 view of the grounding strip. Fig. 4 is a like view of the driving element.

I prefer to use a thin strip of high electrical conductivity shown in Figs. 1 and 3, and such strip is preferably formed of copper, although any other suitable metal may be used as a substitute therefor. This strip, indicated at 1, may be of any desired length and width and is bent into semi-tubular or semi-cylindrical form, as shown, and has the lower extremity thereof attached to a driving point 2. The driving point 2 is a cone-shaped body, as illustrated in Figs. 1 and 2 and at its upper end it is reduced to form a cylindrical shank 3 which, at its junction

with the body of the point, forms an annular driving shoulder 4.

The grounding strip 1 may be attached at its lower end to the driving point 2 in any suitable way such as by soldering and the grounding wire indicated at 5 may be connected to the strip 1 at any suitable point but preferably near the upper extremity thereof, as shown in Fig. 1.

In connection with the driving point 2, I employ a driving element 6 which is preferably tubular and of a size adapting one extremity thereof to fit over the shank 3 of the driving point and rest against the impact shoulder 4 thereof. It will now be understood that with the parts brought together 65 in the manner indicated in Fig. 1, by using a sledge or other suitable implement and striking blows upon the upper end of the tube 6, the device may be driven to any desired depth into the ground, the wire 5 having 70 previously been attached to the grounding element 1.

In order to facilitate the extraction or removal of the driving element 6, a shoulder 7 is provided at or near the upper end thereof, 75 said shoulder being conveniently shown in the form of a fixed collar or flange extending around the tubular driving element and embodying a flat lower face perpendicular to the major axis of the driving element so that 80 blows may be imparted to the shoulder 7 from the under side thereof, thereby knocking the driving element loose from the driving point 2 and enabling the same to be readily withdrawn from the ground. The hole 85 formed by the device may then be filled up.

The semi-tubular or semi-cylindrical construction of the grounding strip imparts several advantageous features to the grounding device; first, the grounding strip of the 90 form described and shown provides for a larger area of contact between the grounding strip and the earth in contact therewith; furthermore it provides for drainage all around the grounding strip; it additionally 100 prevents the formation of a water holding pocket such as would result with the grounding element of full tubular form instead of partially tubular form. While providing all of the advantages referred to, the semi-tubular form of the grounding strip imparts thereto the necessary strength and rigidity 105 to allow for the driving or planting of the

grounding strip without danger of distortion from its original shape.

I claim:

The combination of a driving point having a cylindrical body, a reduced shank at the upper end of the body, and an annular impact shoulder around the shank, and a grounding strip partially embracing and fastened to the body of the driving point 10 outside of the plane of the impact shoulder

and extending upwardly therefrom, said grounding strip being semi-cylindrical in cross section.

In testimony whereof I affix my signature in presence of two witnesses.

GEORGE A. BISHTON.
